UNITED STATES PATENT OFFICE.

WILLIAM W. AMOS, OF OLATHE, KANSAS.

IMPROVEMENT IN SPRING BED-BOTTOMS.

Specification forming part of Letters Patent No. **155,278**, dated September 22, 1874; application filed April 11, 1874.

To all whom it may concern:

Be it known that I, WILLIAM W. AMOS, of Olathe, in the county of Johnson and State of Kansas, have invented a new and valuable Improvement in Bed-Bottoms; and I do hereby declare that the following is a full, clear, and exact description of the construction and operation of the same, reference being had to the annexed drawings, making a part of this specification, and to the letters and figures of reference marked thereon.

Figure 1 of the drawings is a longitudinal sectional view of my spring bed-bottom, and Fig. 2 is a transverse sectional detail view of the same.

This invention has relation to invalid and other spring-beds; and consists in the novel construction and arrangement of parts, as will be hereinafter more fully described and claimed.

In the accompanying drawings, the letter A designates an ordinary bedstead-frame, having side ledges a to support the spring bed-bottom. At the ends of these ledges next the head-board are provided ratchets b, in which the pawls of the adjustable head-frame are adjusted to bring it into a higher or lower position. B designates the transverse spring-frames, which support the longitudinal slats c of the bed-bottom. Along the outer edges of these slats c are arranged series of hooks k, suitably spaced for the passage of the fastening-cord n under said hooks, and over the bed-slats, which are thus interwoven in the cord, and bound thereby on the upper surface of the uppermost spring-slat. These hooks k are turned inward—that is to say, downward in the upper slat, and upward in the lower slat—

to better secure the cord and prevent catching into and tearing the bed-ticking. These spring-frames, being reversible, are turned when permanently bent down by use, the slats re-corded on the other side, and the bed-bottom is thus brought up into comfortable shape. Two of these transverse spring-frames are generally sufficient, one being located near the head, the other near the foot, of the bed-bottom. C indicates the adjustable head-frame. This consists of longitudinal slats l, arranged to fit in the spaces between the bed-slats c, and connected at their rising ends by a transverse tie, m, attached to their upper surfaces, and at their other ends, which are below the bed-slats c, by a similar tie, s, attached to their lower surfaces.

For the purpose of raising the head-frame, a strap or cord, u, may be attached to the upper tie m, and it may be readily lowered by means of an operating-cord, z, attached to a transverse rod, g, connecting the props near their lower ends.

What I claim as new, and desire to secure by Letters Patent, is—

The combination, with the bed-slat c and the reversible spring-frames B, of the binding-cord n and the double series of hooks k, turned inward or toward each other, substantially as specified.

In testimony that I claim the above I have hereunto subscribed my name in the presence of two witnesses.

WILLIAM WILSON AMOS.
